UNITED STATES PATENT OFFICE.

ALBERT W. ENGEL, OF CHICAGO, ILLINOIS.

MERCHANDISE CONTAINER.

Application filed August 10, 1925. Serial No. 49,275.

The purpose of this invention is to provide a receptacle in the nature of a folded paper box adapted to serve as a shipping carton for merchandise and also arranged to be used on the store counter as a receptacle for the goods and as a display device for advertising them. It consists of certain features and elements of construction in combination as herein shown and described and as indicated by the claims.

10 In the drawings:

Figure 1 is a plan view of a blank for a box embodying this invention.

Figure 2 is a perspective front view of the box arranged for use on the counter.

15 Figure 3 is a perspective view showing the rear of the same.

Figure 4 is a perspective rear view showing the box in open position for access to its contents.

20 Referring first to the blank shown in Figure 1 the area which is to become the front wall, as shown in Figure 2, is the rectangular portion, 1, adjoining which is the top, 2, and bottom, 3. A rear wall, 4, is attached to the 25 bottom, 3, at the folding line, 5, and an enclosing cover flap, 6, extends from the scored line, 7, which divides it from the top wall, 2. It will be understood that the terms "top", "front" and "bottom" and the like are used 30 merely with reference to the position of the box as shown in Figure 2. Extending from the front wall, 1, are outer side walls, 8, 8, with folding terminal portions, 9, 9, which are to be bent around the rear wall, 4, along 35 the scored lines, 10. Tabs, 11, interlocking with cut out portions, 12, in the wall, 4, serve as fastening means for holding the box in folded form. These tabs are no part of the 40 present invention being more fully described and claimed in my U. S. Patent Number 1,573,149.

Inner side walls, 13, 13, extend as tabs from the bottom wall, 3, and overlap the inner surfaces of the side wall, 8, when in folded 45 position. Between the inner and outer side walls, 8 and 9, quadrant shaped guide members, 14, 14, are slidably engaged, being completely concealed between said side wall members when the top, 2, is in closed position as 50 shown in Figures 2 and 3.

When the box has been filled and the top, 2, is closed the cover flap, 6, is folded down against the back wall, 4, and its angular tabs, 6^a, are tucked under the tabs, 9^a, the normal stiffness of the material tending to hold 55 the parts thus interlocked.

When the package reaches the hands of the dealer, the cover flap, 6, is disengaged from the tabs, 9^a, and folded back at an angle of about 90° to the top wall, 2, so as to 60 stand upright as shown in Figure 2. It is intended that the front surface of the cover, 6, shall carry advertising matter at 16 and also that the front wall, 1, and top wall, 2, of the 65 box shall likewise be utilized for display purposes.

For holding the part, 6, firmly in upright position, a slide member, 15, is engaged under ears or lugs, 17, extending from the parts, 9, and downwardly extending legs, 15^a, pass 70 through the openings, 12, for additional guidance. Lateral projections, 15^b, extend beyond the slotted openings, 12, and thus serve as stops to limit the upward sliding movement of the part, 15.

With the parts in the position described and shown in Figures 2 and 3, the contents of the box are fully enclosed and guarded from dust. To obtain access to the contents the part, 6, is grasped and lifted to the position shown in Figure 4 thus swinging the top wall, 2, upwardly and bringing the curved parts, 14, out from between the side walls, 8 and 13. These quadrants, 14, are provided with stop lugs, 14^a, which engage apertures, 18, in the rear edges of the box at the upward limit of this movement. If necessary to give proper access to the contents the slide, 15, may be pushed down as shown in Figure 4 so that its upper edge comes even with the top of the 90 back wall, 4, but usually this will not be necessary and after removal of part of the contents the top, 2, will be swung down to closing position with the cover flap, 6, standing upright again as shown in Figure 2.

95 I claim:—

1. In a folded box, including front and back walls and a cover hinged to the front wall, side walls for the box, laterally attached flaps on the cover, each extending adjacent 100 one of the side walls, each side wall having an integral portion folded at right angles at its rear edge engaging the back wall and having an aperture substantially at said fold of the rear edge; and lugs on the flaps positioned 105 to enter said apertures to limit the opening movement of the cover.

2. In the combination defined in claim 1, a slide member engaged with the back wall of the box and movable upward to overlap the 110 vertically extending flap for supporting it.

3. In the combination defined in claim 1,

a slide member engaged with the back wall of the box and movable upward to overlap the vertically extending flap for supporting it, said slide having downwardly extending leg portions entered in slits in the back of the box and laterally projecting stop lugs on said portions for limiting the upward movement of the slide.

4. In a folded box, including front and back walls, a top cover hinged to the front wall and a flap extending from the side of the cover opposite its hinged edge for fold-

ing upwardly in substantially the same vertical plane as the back wall when the cover is closed; side walls having lateral extensions 15 folded against the back wall and secured thereto and a slide member having legs extending through openings in the back wall and an upper portion adapted to lap over the back of the flap for reinforcing it, together with guide ears on the side wall extensions overlapping the slide adjacent the upper part of the back wall.

ALBERT W. ENGEL.
